UNITED STATES PATENT OFFICE

JOSEPH GOULDBOURN, OF LEICESTER, ENGLAND, ASSIGNEE TO UNITED SHOE MACHINERY CORPORATION, OF PATERSON, NEW JERSEY, A CORPORATION OF NEW JERSEY

FASTENING-INSERTING MACHINE

Application filed October 26, 1926, Serial No. 144,364, and in Great Britain November 6, 1925.

This invention relates to fastening inserting machines and is illustrated herein as embodied in a loose nailing machine of a well known type having a swinging head carrying a reciprocating awl arranged to penetrate the work and then to feed the work as the head swings, and a spring-operated driver arranged to insert nails in the holes formed in the work by the awl.

Machines of this type, of which the machine disclosed in United States Letters Patent No. 490,624, granted January 24, 1893, on an application of Louis Goddu, is an example, have been for many years and are now used extensively for various purposes in the manufacture of boots and shoes.

As machines of this type have heretofore been built, it has been found that if they are speeded up beyond about 350 or 375 revolutions per minute the motion of the swinging head is too violent, causing excessive vibration and consequent wear and interfering with, or at least making difficult, the control of the work by the operative as it is fed through the machine. In this connection it should be remembered that the swinging or moving head of such a machine is heavy and that, as these machines have been built, the raceway and, in many instances, the hopper from which nails are supplied to the raceway, swing with the head of the machine, thus increasing the mass of metal which must be moved rapidly back and forth and the direction of movement of which must be reversed twice in each cycle of operation of the machine.

It is, accordingly, an object of the present invention to provide an improved fastening inserting machine of the type having a moving head carrying an awl arranged to penetrate the work and, as the head is moved, to feed the work, which is so organized that it can be operated at a substantially higher speed than is practicable with such machines as heretofore constructed.

In order to enable such a machine to operate smoothly and satisfactorily at a high speed, for example in the neighborhood of 500 revolutions per minute, I have, as illustrated herein, provided a swinging head loose nailing machine so organized that the transverse back-and-forth movement of the swinging head of the machine occupies not substantially less than about one-half of the cycle of operation of the machine. Preferably, the work feeding movement of the swinging head occupies rather more than one quarter, as illustrated one hundred degrees, of the cycle of operation. Thus the head swinging movement occupies, relatively speaking, so much more of the cycle of operation than has been the case heretofore in the operation of machines of this type that the machine may be speeded up very considerably without excessively speeding up the movement of the swinging head. In order to do this I have found it necessary to redistribute in the cycle of operation of the machine the motions of various other parts as more fully hereinafter set forth.

While the invention is disclosed as embodied in a swinging head fastening inserting machine, it should be understood that it is not necessarily limited to machines having that kind of head movement.

With the above and other objects in view the invention will now be described with reference to the accompanying drawings of an illustrative machine, and will be set forth in the accompanying claims.

In the drawings,

Fig. 1 is a front view of the head of a fastening inserting machine embodying the present invention;

Fig. 2 is a diagrammatic view showing the timing of the cam motions of a number of the parts of the machine;

Fig. 3 is a side elevation, with parts in sections, of the clutch and brake mechanism of the machine;

Fig. 4 is an end elevation of the mechanism of Fig. 3 with the main cam shaft of the machine in cross section; and

Fig. 5 is a cross section on an enlarged scale 5 on the line V—V of Fig. 3.

In accordance with the usual construction of swinging head fastening inserting machines the illustrated machine is provided with a main cam shaft 10 concentric with the 10 forward end of which is a swinging head 12 mounted in suitable arcuate guides 14. Reciprocal in ways carried by the swinging head is an awl bar 16 carrying an awl 18 and a driver bar 20 carrying a driver 22. The 15 swinging movement of head 12 and the reciprocation of awl bar 16 and awl 18 transversely of the swinging movement of the head are caused by suitable cams mounted upon shaft 10 and connected to those parts, for example, 20 as set forth in said Letters Patent No. 490,624. Similarly, the upward movement of driver bar 20 is caused by the engagement of a lifting cam 24 carried by shaft 10 with a lifting block 26 clamped to driver bar 20. A spring 25 28 anchored at one end to a stationary part of the head of the machine and connected at the other end by a link 30 with driver bar 20 forces the driver bar and driver downwardly when cam 24 passes out from under block 26, thus driving a nail into the work, and is compressed as cam 24 lifts the driver bar 20. Also carried by the swinging head 12 is a raceway 32 the passage of nails from which to the throat 34 of the machine is 30 controlled by a separator 36 which is also operated from a cam upon shaft 10. The above parts and their relation to each other, except for the timing of their motions and the form and arrangement of the cams by which they 35 are driven, may be and, as illustrated, are, of the character set forth in said Letters Patent No. 490,624, to which reference may be had for a fuller description thereof. To support the work as the fastenings are inserted the 40 machine is provided with a horn 38 arranged to clamp the work against a presser plate 40 which limits its upward movement. The horn 38 is moved downwardly prior to the feeding movement of the swinging head and 45 awl to release the pressure from the work and upwardly to clamp the work against pressure plate 40 prior to the insertion of each fastening by suitable release mechanism, for example as disclosed in Letters Patent of the 50 United States No. 265,227, granted September 26, 1882, on an application of Louis Goddu, also driven from cam shaft 10.

In the illustrated machine the timing of 55 the movement of the swinging head is such that the machine may be driven at an increased speed of about 500 revolutions per minute without substantially increasing the velocity (as compared with the old slower machines) at which the work is fed through

the machine by the movement of the swinging head and the awl, and without substantially increasing the speed of the return movement of the awl. Thus, too jerky a movement of the work through the machine and violent shaking or vibration with consequent excessive wear of the swinging head or other parts of the machine and interference with the control of the work by the operative are avoided. 70

With this purpose in view the back-and-forth movement of the swinging head of the illustrated machine is, as shown at D in the cam diagram of Fig. 2, distributed through about 180° of the cycle of operation of the machine, the feeding movement occupying 80 about 100° and the return movement about 75°. In order to devote this large portion of the cycle of operation of the machine to the movement of the swinging head the speed of the reciprocating motion of the awl has 85 been relatively increased, so that the descent and ascent of the awl each occupies less than 40° of the cycle, as shown at B in Fig. 2. Also, the downward movement of the horn as 90 shown at C to release the pressure upon the work begins substantially simultaneously with, or even a little before, the completion of the downward movement of the awl and the feeding movement of the head starts somewhat before the horn reaches its lowermost position and continues during something like one half of the upward pressure applying movement of the horn. Moreover, 95 the withdrawal of the awl from the work begins long before the completion of the upward movement of the horn, the two ending substantially simultaneously. These movements are clearly shown in the timing diagram of Fig. 2 in which A represents the 100 driver timing, B the work penetrating and withdrawing movement of the awl, C the downward pressure releasing and upward pressure applying movement of the horn or work support, D the swinging movement of 105 the head, E the separator movement and F the movement of the brake applying lever which, however, is idle except toward the end of the last cycle of operation when the machine is being brought to rest. In considering this diagram it should be remembered that machines of this character come to rest with the driver down. There will be some slight variation, however, in the position of the main cam shaft 110 when the machine comes to rest according to the distance that that shaft moves after the clutch is thrown out and the brake applied. Referring to Fig. 2, if the machine comes to rest anywhere within the first 20° of the diagram it is operating satisfactorily and will 115 be ready to start again whenever the clutch is thrown in and the brake released. 120

The relation of the timing of the various parts of the illustrated machine will best be 125 130

understood from the following table taken in connection with the diagram of Fig. 2.

Angle from point of driver descent	
5	20°—Awl begins to descend.
	55°—Awl fully down.
	55°—Horn begins to drop.
	60°—Separator begins to move back to in-operative position.
10	100°—Feed begins.
	110°—Horn down.
	115°—Separator back.
	155°—Driver begins to rise.
	185°—Horn begins to rise.
15	200°—Feed ends.
	215°—Separator begins to move forward to separate.
	225°—Awl begins to rise.
20	240°—Separator dwells.
	245°—Awl begins to return for new feed.
	255°—Horn fully up.
	260°—Awl fully up.
	270°—Separator recommences forward movement.
25	300°—Driver up.
	300°—Brake begins to come on (in last cycle only).
	310°—Separator fully forward.
	320°—Awl returned to new feed position.
30	320°—Brake on (in last cycle only).
	360°—Driver falls.

The illustrated machine is also provided with improved clutch controlling mechanism shown particularly in Figs. 3, 4 and 5. Thus, the cam shaft 10 of the machine has rotatably mounted upon it a driving pulley 50 which, when the machine is to be driven, is moved axially of the shaft, to cause a clutch surface 52 formed thereon to engage with a corresponding clutch surface of a clutch member 54 fixed upon shaft 10. A spring 56 surrounding shaft 10 bears at one end upon a collar 58 secured to shaft 10 and at the other upon a sleeve 60 keyed to shaft 10 and forming a bearing for pulley 50. At the opposite end of the sleeve 60 is a washer 62 against which bear the ends of a plurality of rods 64 mounted in the hub 65 of the clutch member 54. The rods 64 also bear upon the rear of a wedge member or block 66 slidably mounted on shaft 10 and engaging a wedge member 68 mounted for movement transversely of shaft 10 upon a yoke member 70. Thus, when yoke member 70 is moved downwardly, wedge member 68 will force wedge member 66 to the left, as viewed in Fig. 3, thus pushing rods 64, washer 62, sleeve 60 and pulley 50 to the left against the compression of spring 56 and disengaging the clutch surfaces of clutch members 50 and 54 so that shaft 10 is no longer driven. On the other hand, when yoke member 70 is moved upwardly the upward movement of wedge member 68 permits wedge member 66 to be moved

to the right, permitting spring 56 to force sleeve 60 and pulley 50 to the right so that the clutch surfaces of clutch members 52 and 54 engage and power is transmitted to shaft 10.

Yoke 70 is pivotally connected at its lower end by a link 72 with a lever 74 fulcrumed upon a shaft 76 carried at 78 (Fig. 3) by the frame of the machine. Lever 74 has a downwardly extending arm 80 (Fig. 4) to which is pivoted at 82 a latch member 84, at the left-hand end of which is a hardened latch block 86. Fulcrumed concentrically with lever 74 is a second lever 88 extending approximately vertically and carrying at its upper end a cam roll 92 operating in a cam track 90 formed in a cam carried by the shaft 10. At its lower end lever 88 is provided with a hardened latch block 94 arranged when the machine is at rest to engage with the latch block 86, as shown in Fig. 4, thus holding lever 74 in the position shown in that figure with the yoke 70 depressed so that the clutch is disengaged. A tension spring 96 tends to rock lever 74 in a counter-clockwise direction, as shown in Fig. 4, while a second spring 98 tends to rotate latch member 84 in a clockwise direction. A rod 100, movable upwardly by a treadle 102 and downwardly by a spring 104 when the treadle is released, is moved upwardly against the tail of latch 84 when the machine is to be started. Thus block 86 is moved downwardly so that lever 74 is released and is rotated in a counter-clockwise direction by spring 96. This forces yoke 70 and wedge 68 upwardly, permitting movement of wedge 66 to the right, as viewed in Fig. 3, under the influence of spring 56 so that, as hereinbefore set forth, shaft 10 is driven by the clutch. When the treadle is released, however, to stop the machine, the rod 100 descends and latch member 84 is rotated in a clockwise direction by spring 98. Lever 88, which oscillates idly while the machine is running until after the treadle is released, moves in such a path that block 94 engages block 86 at a definite point in the cycle of operation after rod 100 has been lowered, so that lever 74 is rocked by lever 88, forcing yoke 70 and wedge member 68 downwardly and thereby moving wedge 66 to the left, compressing spring 56 and disengaging the clutch members.

In order to bring the machine to rest promptly after the clutch is disengaged a brake band 106 is provided engaging a brake drum 108 fast upon cam shaft 10. Brake band 106 engages drum 108 through almost its entire periphery. In order to tighten brake band 106 upon drum 108 the left end of brake band 106 (as viewed in Fig. 4) is mounted upon an eccentric 110 (Figs. 3 and 4) fixed to a sleeve 112 projecting from and coaxial with the hub of clutch lever 74 so that as the clutch lever 74 is rocked to disengage

the clutch, eccentric 110 is rotated to move the left-hand end of brake band 106 into engagement with drum 108. The other end of brake band 106 is connected by an adjustable rod 114 to clutch lever 74 so that as the clutch lever moves to disengage the clutch it will also pull the right-hand end of brake band 106 into engagement with brake drum 108. Since the lever 88 is operated by a closed cam 10 the brake is positively applied and may be adjusted by adjusting the connection of brake band 106 to rod 114.

To release the brake and permit cam shaft 10 to be rotated, if desired, while the machine is at rest, the end of the rod 114 remote from brake band 106 is mounted on an eccentric stud 116 which may be rotated by a hand lever 118 connected thereto provided for that purpose. Eccentric stud 116 is provided with a pair of notches or recesses 120, 122 (Fig. 5) either one of which may be engaged by a spring pressed plunger 124 mounted in the lever 74 to hold the stud 116 in either brake applying or brake releasing 20 position. To prevent accidental engagement of the clutch when the brake is thus released eccentric stud 116 has fixed to it a cam or stop member 125 which, when the stud is rotated to release the brake, is moved against 25 a fixed abutment 126 to prevent movement of clutch lever 74 in a direction to allow the clutch members to engage.

The clutch operating mechanism disclosed in this application is not claimed herein since 35 it forms the subject-matter of Letters Patent of the United States No. 1,696,535, granted December 25, 1928 on an application filed in my name.

Having described my invention, what I 40 claim as new and desire to secure by Letters Patent of the United States is:

1. A cyclically operating machine for inserting fastenings in boot and shoe parts having a transversely moving head, an awl and a 45 driver carried by said head for transverse movement therewith and reciprocable in paths substantially at right angles to its transverse movement to cause the awl to penetrate the work and cause the driver to insert 50 fastenings in the holes formed by the awl in the work, and means for moving the head transversely of the machine whereby the awl, moving with the head, feeds the work, said means being arranged to cause the transverse 55 movement of the head to occupy substantially one-half of the cycle of operation of the machine whereby the machine may be run at a relatively high speed without speeding up the feeding movement of the work through 60 the machine.

2. A cyclically operating machine for inserting nails in boot and shoe parts having a transversely swinging head, an awl carried by the swinging head and mounted for trans- 65 verse work feeding movement with the head

and for reciprocation substantially at right angles to its transverse movements to penetrate and withdraw from the work, a driver carried by the swinging head arranged to insert fastenings in the holes formed by the awl in the work, a raceway carried by the head and swinging therewith arranged to supply fastenings to be inserted by the driver in the holes formed in the work by the awl, and a cam operatively connected to the head to swing the head and the raceway back and forth transversely of the machine, said cam being formed and arranged to cause said swinging movement of the head and the raceway to occupy substantially one-half of the 70 cycle of operation of the machine. 75

3. A cyclically operating machine for inserting fastenings in boot and shoe parts having a transversely moving head, an awl carrier reciprocable in a guide carried by the head, an awl carried by said carrier and arranged to penetrate and withdraw from the work, a driver bar also reciprocable in a guide carried by the head, a driver carried by the driver bar and arranged to insert fastenings in the holes formed in the work by the awl, and means for moving the head back and forth transversely of the machine to cause the awl to feed the work and to return, arranged to cause the transverse back and forth movement of the head of the machine to occupy not substantially less than about one-half of the 80 cycle of operation of the machine. 85

4. A cyclically operating machine for inserting fastenings in boot and shoe parts having a transversely swinging head, an awl carried by the swinging head for transverse movement therewith and reciprocable in a path substantially at right angles to its transverse movement to penetrate the work, a driver carried by the swinging head arranged to insert fastenings in the holes formed by the awl in the work, a cam, and connections from the cam to the head to cause the cam to swing the head transversely of the machine whereby the awl, moving with the head, feeds the work, said cam and connections being formed and arranged to cause the feeding movement of the head and awl to occupy rather more than a quarter of the cycle of 90 operation of the machine. 95

5. A cyclically operating machine for inserting nails in boot and shoe parts having a transversely swinging head, an awl carried by the swinging head for transverse work feeding movement therewith and reciprocable in a path substantially at right angles to its transverse movement to penetrate and withdraw from the work, a driver also carried by the swinging head arranged to insert 100 nails in the holes formed by the awl in the work, a throat member carried by the swinging head and provided with a driver passage in alignment with the driver, a raceway carried by the head and swinging therewith 105

arranged to conduct nails to the throat member, means for swinging the head transversely of the machine to cause the head by engagement of the awl with the work to feed the work between the insertion of successive nails and to return the head between its feeding movements, said head swinging means being arranged to cause the feeding movement of the head to occupy substantially one hundred degrees of the cycle of operation of the machine whereby the machine may be driven at a relatively high speed without excessive wear of the head swinging parts and without interference with the satisfactory feeding of the work.

5. A cyclically operating machine for inserting fastenings in boot and shoe parts having a transversely moving head, an awl carried by said head for transverse back and forth movement therewith and reciprocable in a path substantially at right angles to its transverse movement to penetrate and withdraw from the work, a driver also carried by said head arranged to insert fastenings in the holes formed by the awl in the work, means for moving the head transversely of the machine to cause the head by engagement of the awl with the work to feed the work between the insertion of successive fastenings and to return the head between its feeding movements, said means being arranged to cause the transverse back and forth movement of the head to occupy substantially one-half of the cycle of operation of the machine whereby the machine may be run substantially faster than prior moving head fastening inserting machines without the speed of the feeding movement of the work through the machine being substantially changed.

6. A cyclically operating machine for inserting fastenings in boot and shoe parts having a transversely swinging head, an awl carried by said head and mounted for transverse work feeding movement with the head and for reciprocation substantially at right angles to its transverse movement to penetrate and withdraw from the work, a driver carried by said head arranged to insert fastenings in the holes formed by the awl in the work, a shaft, and means operated thereby for swinging the head back and forth transversely of the machine arranged to cause said back and forth movement of the head to occupy substantially one-half of the cycle of operation of the machine and thereby to eliminate excessively fast swinging of the head and the vibration and wear incident thereto.

7. A high-speed, cyclically operating machine for inserting fastenings in boot and shoe parts having a transversely swinging head, an awl carried by said head and mounted for transverse work feeding movement with the head and for reciprocation substantially at right angles to its transverse movement to penetrate and withdraw from the work, a driver carried by said head arranged to insert fastenings in the holes formed by the awl in the work, a shaft, and a cam carried by the shaft arranged to give to the awl its transverse work feeding and return movements formed to cause said work feeding and return movements to occupy together substantially one-half of the cycle of operation of the machine.

8. A cyclically operating machine for inserting fastenings in boot and shoe parts having a head, an awl carried by the head and mounted for transverse work feeding movement and for reciprocation substantially at right angles to its transverse movement to penetrate and withdraw from the work, a driver carried by said head arranged to insert fastenings in the holes formed by the awl in the work, a rotating shaft, and means operated thereby to give the awl its work feeding movement arranged to cause the work feeding movement of the awl to occupy not less than one-quarter of the cycle of operation of the machine.

9. A cyclically operating machine for inserting fastenings in boot and shoe parts having a head, an awl carried by said head and arranged to penetrate the work, then to move transversely of its work penetrating movement to feed the work, then to withdraw from the work, and then to move transversely in a direction opposite to its work feeding movement thereby returning to its starting position, a driver carried by said head and arranged to insert fastenings in the holes formed by the awl in the work, a rotating shaft, and a cam carried by the shaft arranged to give to the awl its transverse work feeding and return movements formed to cause said work feeding and return movements to occupy together substantially one-half of the cycle of operation of the machine.

10. A fastening-inserting machine having a transversely swinging head, an awl and a driver carried thereby mounted for transverse work feeding movement with the head and reciprocating work penetrating and withdrawing movement relatively to the head, an abutment arranged to limit movement of the work toward the awl and driver, a work support movable toward and from the abutment and arranged to force the work against the abutment during the insertion of the awl in the work and during the driving of the fastenings, and means for moving the work support from the abutment to release the pressure upon the work during the feeding movement of the awl and then to return the work support to pressure applying position arranged to start the pressure applying return movement of the work support substantially before the start of the withdrawal of the awl from the work.

11. A fastening-inserting machine having a transversely swinging head, an awl and a driver carried thereby mounted for transverse work feeding movement with the head and reciprocating work penetrating and withdrawing movement relatively to the head, an abutment arranged to limit movement of the work toward the awl and driver, a work support movable toward and from the abutment and arranged to force the work against the abutment during the insertion of the awl in the work and during the driving of the fastenings, and a cam for moving the work support from the abutment to release the pressure upon the work during the feeding movement of the awl and for returning the work support to pressure applying position arranged to start the pressure applying

return movement of the work support substantially before the start of the withdrawal of the awl from the work and to complete the withdrawal of the awl from the work not substantially later than the completion of the pressure applying movement of the work support.

12. In a fastening inserting machine having a transversely swinging head, an awl carried by the head and mounted for transverse work feeding movement with the head and for reciprocation substantially at right angles to its transverse movement to penetrate and withdraw from the work, a driver also carried by the head arranged to insert fastenings in the holes formed by the awl in the work, a cam connected to the head and arranged to swing the head transversely of the machine thereby causing the awl to feed the work between the insertion of excessive fastenings, said cam being formed to cause the transverse back-and-forth movement of the head to occupy not less than substantially one-half of the cycle of operation of the machine, an abutment and a work support between which the work is clamped during both the work penetrating movement of the awl and the insertion of fastenings in the holes formed by the awl, and means for moving the work support from the abutment to relieve the pressure upon the work during the work-feeding movement of the awl and then to return the work support to pressure applying position arranged to start the pressure applying return movement of the work support before the start of the withdrawal of the awl from the work and before the completion of the work feeding movement of the awl.
- 40 In testimony whereof I have signed my name to this specification.
